UNITED STATES PATENT OFFICE.

NÁNDOR KOLÁR, OF BUDAPEST, AUSTRIA-HUNGARY, ASSIGNOR TO AUTOMETRÓ-GRAPH RÉSZVÉNYTÁRSASÁG, OF BUDAPEST, AUSTRIA-HUNGARY, A CORPORATION OF HUNGARY.

PREPAYMENT-METER.

1,205,457.

Specification of Letters Patent. Patented Nov. 21, 1916.

Application filed April 16, 1915. Serial No. 21,916.

To all whom it may concern:

Be it known that I, NÁNDOR KOLÁR, a subject of the King of Hungary, residing at Budapest, in the Empire of Austria-Hungary, have invented certain new and useful Improvements in Prepayment-Meters, of which the following is a specification.

The known coin freed or prepayment meters have the drawback that the control is very complicated and connected with great expense and that the customer receives no receipt in respect of the amount taken by the apparatus. According to this invention these drawbacks are obviated in the following manner: The receiving receptacle for the inserted coins is connected in a known manner with a collecting receptacle which is accessible solely to the controlling official and to which the coins are conveyed from the receiving receptacle by mechanism operated by the meter according to the extent of the consumption. Now, in accordance with this invention the collecting receptacle is connected to a printing counting apparatus adapted to print a receipt and indicating the number of the coins contained in the collecting receptacle, that is to say, the corresponding amount in money at the time being, so that the collecting receptacle can be opened after being emptied only after issue of the receipt and after the printing counting apparatus has been reset to zero. Of the receipts which, by preference, are issued in two copies, one is allotted to the customer and the other serves to control the collecting official.

The accompanying drawing illustrates by way of example, a constructional form of the invention.

Figure 1 shows a vertical longitudinal section of a meter construction provided with the improvements. Fig. 2 a transverse section on the line 2—2 of Fig. 1. Fig. 3 a transverse section on the line 3—3 of Fig. 1. Fig. 4 indicates the manner in which the inserted printing frame releases the locking arrangement of the collecting receptacle.

The coins 5 are introduced through a slot

1 and passing through the slot 2 of a drum 4 rotatable by means of a handle 3, drop 50 during the rotation of the drum successively into a receiver 6 in which they are piled up. As the drum 4 rotates, the coins in their passage to the receiver 6 actuate a ratchet wheel 32 of a counting train which indicates the 55 number of the coins contained in the receiver 6 in a known manner.

Below the receiver 6 is a slide 13 supported by rollers 12. This slide receives reciprocating movement from the meter shaft 60 17 by means of an appropriate transmission gear 16, connecting rod 15 and fork 14 whereby the slide 13 receives one forward and one backward movement every time the meter registers due to the insertion of a coin 65 in the apparatus. By means of a known intermittently acting gear 18, moreover, the shaft 19 which drives the counting apparatus is intermittently rotated. This shaft has attached to one of its ends a crank 20 70 operated by which in upward and downward direction is a push rod 21 carrying a toe 22.

Attached to the casing is a collecting receptacle 7 adapted to receive the coins released from the receiver 6 by the action of the meter. The receptacle 7 is attached to the part 9 of the casing by means of a bayonet joint 8 and is provided with a locking pin 10 engaging with a spring actuated 80 bolt 11, thereby preventing the removal or opening of the collecting receptacle 7.

From the shaft 17 driven by the meter is actuated, on the one hand the counting train 23 indicating the consumption of the meter 85 and on the other hand, the counting train 24 which indicates the amount corresponding to the consumption, that is to say, the amount contained at the time being in the collecting receptacle 7. This latter counting train 24 is provided with a known zeroizing device by which the counting train is reset to zero. The casing 25 is provided with an opening 26 controlled by a door adapted for the introduction into the apparatus of a well-known printing frame 88 95

(Fig. 4) which contains the receipt to be printed (if desired in several copies) and the printing mechanism. Arranged, moreover, in the casing is a two-armed lever 28, 5 29 pivoted at 27 and flexibly connected to the spring actuated bolt 11.

The operation is as follows: The reciprocating slide 13 actuated by the meter releases the individual coins 5 from the receiver 6 and always precisely at the instant 10 in which the unit of consumption or the corresponding amount is registered by the counting trains 23, 24, the toe 22 on the rod 21 pushes the coin 30 located on the 15 slide 13 through the opening 31 into the collecting receptacle 7. The precise coincidence of the registration and of the delivery of the coin is attained by driving both the counting trains 23, 24 and the push rod 21 simultaneously by the same intermittently acting gear 18.

In order to enable the collecting clerk to withdraw the money from the collecting receptacle he must, first of all insert the printing frame 33 through the opening 26 into the apparatus. The printing frame on being inserted strikes by means of its end 34 against the lever arm 29 thereby causing the lever arm 28 to withdraw the bolt 11 in 25 order to release the locking pin 10 of the collecting receptacle 7. The bayonet joint 8 may now be released and the collecting receptacle 7 detached from the casing portion 9 and emptied. The printing frame is 30 inserted in a well-known manner. It cannot be withdrawn from the apparatus without previously printing the record on the counting trains 23, 24 and zeroizing of the train 24 so that the printing frame after being 35 withdrawn contains two or more copies of the receipt for the amount contained in the collecting receptacle, of which one copy is used for the customer and the other for the company to control the amount taken by 40 the collector.

The device may be varied in many ways without departing from the spirit of the invention. For instance, the counting train 50 24 may be omitted and the counting train producing the receipt may indicate only the number of coins contained in the receptacle 7 instead of the amount thereof. Moreover, the counting train need not be constructed as a printing mechanism since the receipt 55 may be marked in other ways, for instance, by punching, if a previously printed form is employed, the number of punched holes corresponding to the number of coins in the collecting receptacle 7. The mechanism, 60 moreover, is so arranged in a known manner that the supply of gas is automatically cut off by a valve as soon as the coins in the receptacle 6 are exhausted. The collecting receptacle after being emptied may be put

in place, in which action the pin 10 again engages with the locking bolt 11, thus securing the collecting receptacle 7 in its position. Since the door controlling the opening 26 can be opened only by means of a key, the access to the lever 29 is possible only for authorized persons.

What I claim and desire to secure by Letters Patent is:—

1. In a prepayment meter, a receipt recording means; a coin receptacle; a locking device connected to the meter and adapted to hold the coin receptacle locked until the receipt recording means is operated.

2. In a prepayment meter, a recording means; a coin receptacle; a locking device connected to the meter and adapted to hold the coin receptacle locked until after the recording means has made a record.

3. In a prepayment meter, a recording means; a coin receptacle; a locking device connected to the meter and adapted to hold the coin receptacle locked until after the recording means has made a record and has been zeroized.

4. In a prepayment meter, the combination of a coin receiver, a coin collecting receptacle detachable from the meter, a receipt recording frame adapted to coöperate with the counting train of the meter, a mechanism controlling the connection of the collecting receptacle with the meter and actuated by the said receipt recording frame so that the collecting receptacle can be detached only after the receipt has been recorded and the counting train zeroized.

5. In a prepayment meter, the combination of a coin receiver, a coin collector, mechanism for delivering individual coins from the receiver to the said collector, a receipt recording frame, a locking device connecting the collector to the meter and releasing mechanism operated by the receipt recording frame, substantially as set forth.

6. In a prepayment meter, the combination of counting trains, driving mechanism actuating the same, a coin receiver, a coin collector, a reciprocating slide for abstracting individual coins from the said receiver, a vertically reciprocating pusher for delivering the individual coins from the said slide to the collector and means for operating the said slide and the said pusher from the driving mechanism actuating the counting trains of the meter, substantially as set forth.

7. In a prepayment meter, the combination of a coin receiver; a reciprocating slide at the bottom of the receiver; a meter shaft; an operative connection between the shaft and slide for reciprocating the slide; a counting apparatus shaft; a crank on the end of the counting apparatus shaft; a push rod operated by the crank and provided with

a toe adapted to tip a coin from the slide; a
coin receptacle; a locking pin secured to
the receptacle; a spring actuated bolt en-
gaging said pin; a lever connected to said
5 bolt; and a receipt printing frame adapted
to contact said lever for withdrawing the
bolt and releasing the pin.

In testimony whereof I have affixed my
signature in presence of two witnesses.

NÁNDOR KOLÁR.
